UNITED STATES PATENT OFFICE

167,059

FREESTANDING FIREPLACE

Gerald M. Richards, San Francisco, Calif.

Application September 15, 1951, Serial No. 16,648

Term of patent 14 years

(Cl. D81—10)

To all whom it may concern:

Be it known that I, Gerald M. Richards, a citizen of the United States, residing at city of San Francisco, county of San Mateo, State of California, have invented a new, original, and ornamental Design for a Freestanding Fireplace, of which the following is a specification, reference being had to the accompanying drawing, forming a part hereof.

I claim:

The ornamental design for a freestanding fireplace, as shown.

GERALD M. RICHARDS.
